[57] CLAIM

The ornamental design for a picnic cooler, as shown and described.

DESCRIPTION

FIG. 1 is a top, front, left side perspective view of a picnic cooler showing our new design;
FIG. 2 is a top, front, right side perspective view thereof with the handle in lowered position;
FIG. 3 is a front elevational view thereof;
FIG. 4 is a right side elevational view thereof, the opposite side being a mirror image thereof;
FIG. 5 is a rear elevational view thereof;
FIG. 6 is a top plan view thereof;
FIG. 7 is a bottom plan view thereof;
FIG. 8 is a top, front, right side perspective view thereof with the lid reversed; and
FIG. 9 is a top plan view thereof of that shown in FIG. 8.
